BELT ATTACHMENT FOR CARRYING A TAPE MEASURE OR THE LIKE

Charles Zelnick, Saginaw, Mich., assignor to The Lufkin
Rule Company, Saginaw, Mich., a corporation of Michigan

Filed Sept. 24, 1962, Ser. No. 71,820

Term of patent 14 years

(Cl. D58—26)

FIG. 1

FIG. 3

FIG. 4

I claim:

The ornamental design for a belt attachment for carrying a tape measure or the like, as shown.
